UNITED STATES PATENT OFFICE

CHARLES WEISS, OF NEW YORK, N. Y.

DESIGN FOR A PITCHER OR THE LIKE

Application filed June 27, 1929. Serial No. 31,847. Term of patent 7 years.

To all whom it may concern:

Be it known that I, CHARLES WEISS, a citizen of the United States, and resident of the borough of Manhattan, city, county, and State of New York, have invented a new, original, and ornamental Design for a Pitcher or the like, of which the following is a specification, reference being had to the accompanying drawing, forming part hereof, in which—

Fig. 1 is a side elevation and Fig. 2 a top plan view of a pitcher or the like showing my new design.

The dominant feature of the design resides in the shape of the spout and its relation to the body of the pitcher.

I claim:

The ornamental design for a pitcher or the like, as shown and described.

CHARLES WEISS.
